UNITED STATES PATENT OFFICE.

CHARLES H. HESS, OF ZANESVILLE, OHIO, ASSIGNOR TO THE KEARNS-GORSUCH BOTTLE COMPANY, OF SAME PLACE.

DESIGN FOR A JAR-CAP FASTENER.

SPECIFICATION forming part of Design No. 31,435, dated August 22, 1899.

Application filed July 29, 1899. Serial No. 725,540. Term of patent 14 years.

To all whom it may concern:

Be it known that I, CHARLES H. HESS, a citizen of the United States, residing at Zanesville, in the county of Muskingum and State of Ohio, have invented and produced a new and original Design for a Jar-Cap Fastener, of which the following is a specification.

This invention relates to a new and original design for a jar-cap fastener; and it has for its object to provide a design of this character that shall be both useful and ornamental.

The leading feature of the design resides in a straight flat spring provided intermediate its ends with a single rounded crimp projecting at one side thereof, said flat spring being further provided at one end with a sigmoidal-shaped tongue and at its opposite end with an inturned rounded U-shaped hook, said tongue and hook projecting laterally from the same side of the spring as the crimp.

A minor feature of the design resides in having the crimp of a U shape and merging on curved lines into the straight portion of the spring.

In the drawings, Figure 1 is a perspective view of a jar-cap fastener occupying the here-

in-described design. Fig. 2 is a similar view showing the same reversed. Fig. 3 is a side edge view thereof.

Referring to the accompanying drawings, the numeral 1 designates a straight narrow flat spring provided centrally between its ends with a single U-shaped crimp 2, which merges on curved lines into the contiguous straight portions of the spring. The latter is also provided at one of its ends with an integral sigmoidal-shaped tongue extension 3 and at its directly opposite end with an in-turned rounded U-shaped hook 4. The said tongue 3 and the rounded hook 4 project laterally from the same side of the flat spring 1 as the crimp 2.

What is claimed is—

The design for a jar-cap fastener herein shown and described.

In testimony that I claim the foregoing as my own I have hereto affixed my signature in the presence of two witnesses.

CHARLES H. HESS.
